(57) **CLAIM**

The ornamental design for a camera, as shown and described.

DESCRIPTION

FIG. 1 is a top, front, and left side perspective view of a camera showing my new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof; and,

FIG. 8 is a top, rear, right side perspective view thereof.

The broken lines shown in the drawings depict portions of the camera that form no part of the claimed design. The broken lines showing a connector in FIGS. 2 and 8 depict environmental subject matter and forms no part of the claimed design.

1 Claim, 8 Drawing Sheets
